UNITED STATES PATENT OFFICE.

LÉON GAUMONT, OF PARIS, FRANCE, ASSIGNOR TO SOCIÉTÉ DES ÉTABLISSEMENTS GAUMONT, OF PARIS, FRANCE.

SYNCHRONIZING DEVICE.

1,163,079.

Specification of Letters Patent.

Patented Dec. 7, 1915.

Original application filed January 4, 1907, Serial No. 350,857. Divided and this application filed December 2, 1907. Serial No. 404,712.

To all whom it may concern:

Be it known that I, LÉON GAUMONT, a citizen of the French Republic, residing at Paris, France, have invented certain new and useful Improvements in Synchronizing Devices, of which the following is a specification.

This invention relates to certain improvements in that class of devices which are particularly designed and adapted for employment with driven mechanisms for maintaining a synchronous or substantially synchronous relation between such mechanisms, and an object of the invention is to provide a device of this character of a simple and comparatively inexpensive nature by means of which a phonograph and cinematograph, may be maintained in substantially synchronous relation automatically as to permit the reproduction of music, singing, speaking, or other sounds from the phonograph in accurate timed relation to a moving picture exhibition produced by the cinematograph, without the exercise of any particular care or attention on the part of an attendant.

The invention consists in certain novel features of the construction, and combinations and arrangements of the several parts of the improved synchronizing device, whereby certain important advantages are attained and the device is rendered simpler, less expensive, and otherwise better adapted and more convenient for use, all as will be hereinafter fully set forth.

The novel features of the invention will be carefully defined in the claims.

In the accompanying drawings which serve to illustrate my invention—Figure 1 is a somewhat diagrammatic view showing a synchronizing device embodying my improvements; Fig. 2 is a front elevation of the mechanical controlling means comprised in the device as illustrated in Fig. 1, said device being shown adjusted to a position different from that illustrated in Fig. 1; Fig. 3 is a central section taken vertically through the controlling means; Fig. 4 is a somewhat diagrammatic view showing the connection of the motors and the synchronously operated cinematograph and phonograph.

Referring first to Figs. 1 to 4, 1 represents a suitable support or base of any kind

whereon the controlling means comprised in the improved synchronizing device is mounted, said means comprising, as herein shown, a frame formed of spaced members 2, 2 between which is arranged an electric motor 3, the armature shaft 4 whereof is extended across the space between and has bearings in the frame members 2, 2 as clearly shown in Fig. 3 of the drawings.

Below the motor 3, a differential gear device, indicated as a whole at 5, is extended across the space between the frame members 2, 2, its box or casing being provided with alined bosses 8, 8 at its forward and rear ends, which bosses are mounted to turn in suitable bearings in the frame members 2, 2 and serve as bearings wherein turn alined shaft sections 6 and 7 which project, respectively from the rear and front sides of the frame of the device, and carry, within the box or casing similar bevel or miter gears 9 and 10 which mesh with oppositely arranged bevel or miter gears 11, 11 upon a shaft 12 extended transversely across the box or casing of the differential gear device in a direction at right angles to the axes of 80 the alined shaft sections 6 and 7.

The projecting end portion of the shaft section 6 at the rear side of the frame is connected by suitable gearing 14 so as to be driven from the motor 3, and said projecting extremity of the shaft section 6 is adapted to be connected with a phonograph A, as shown in Fig. 4 in such a manner that said phonograph shall be driven from the motor 3 while at the same time, the shaft section 6 and gear 9 of the differential gear device shall be driven in unison with the movement of said phonograph.

The forward end of the shaft section 7, which projects at the forward side of the frame, is provided with a gear wheel 15 with which meshes a gear wheel 16, mounted upon a stud shaft 17 held to turn in a bearing at the upper part of a bracket 18, which bracket is adjustably mounted upon the support 1 so as to be adapted to be adjusted thereon to move the stud shaft 17 nearer to or farther from the shaft section 7 for permitting gears of different relative diameters to be substituted for the gear wheels 15 and 16 so that the device may be accommodated for maintaining different speed ratios between the phonograph and cinematograph B,

from which latter the stud shaft 17 is driven by means of a flexible shaft 19 or the like as shown in Fig. 4.

The detailed construction of the phonograph and cinematograph, in connection with which the improved synchronizing device is herein shown as adapted for use, and the particular characters of the driving connections by means of which the elements of the differential gear device are actuated in unison with said phonograph and cinematograph are immaterial to the present invention and are not illustrated in detail herein, since such features of construction are well known to those skilled in the art.

The forward boss 8 of the box or casing of the differential gear device is formed into a pinion as seen at 20 and said pinion is in mesh with a gear wheel 21 having a hub portion mounted to turn loosely upon a stud 22 upon the frame, there being an index or pointer 23 carried upon the hub of said gear wheel, with its free end directed upwardly in front of the frame and arranged to stand opposite to and play across a gage device 24 at the upper part of the forward frame member 2. By this arrangement of the parts it will be seen that any deviation either of the phonograph A or cinematograph B from the desired relative speeds will serve to move the index or pointer 23 in one direction or the other across the gage device 24, so that such deviation will be indicated to the attendant. This arrangement is substantially like that shown and claimed in my application, Serial No. 350,857, filed January 4th, 1907, now Patent No. 1,144,339, dated June 22, 1915, of which this present application is a division, and I therefore make no claim to the particular construction and arrangement of the parts above described in this present application.

The present invention relates to means for automatically controlling the movements of the phonograph or cinematograph driving devices so as to secure substantial synchronism in the operation thereof, and in carrying out the present invention, as shown in Figs. 1 and 2, I provide means, actuated from the differential gear and controlling the circuit of the cinematograph motor which I will now proceed to describe.

36 represents a contact bar or plate carried by the index or pointer 23 and having its opposite ends adapted in the normal or central position of the index or pointer, as shown in Fig. 1, to contact electrically upon a plate 29 which is included in a partial circuit in shunt with the circuit of the cinematograph actuating motor 25, said shunt circuit including a conductor 33 extended from the plate 29 to the rheostat 28 included in the motor circuit.

26 represents the armature circuit of said

motor 25, connected with a generator 27 or other source of supply and including a switch α , and 26^a represents the shunt field.

30 represents a contact plate similar to the plate 29, but insulated therefrom by a narrow strip 31 of insulating material, and this plate 30 is also included in the partial shunt circuit wherein plate 29 is included, said plate 30 being connected by a conductor 32 with the motor circuit 26 at a point adjacent to one end of the rheostat 28. The conductor 33 has an adjustable connection with the rheostat 28 as shown at 34, so that when desired said conductor may be brought into electrical communication with the rheostat 28 at a point more or less distant from the end whereat the conductor 32 has communication with the motor circuit conductor 26. By this arrangement it will be evident that during the normal operation of the parts, when the index or pointer stands in its central position, as shown in Fig. 1, both extremities of the contact piece 36 resting upon the plate 29, the full length of the rheostat 28 is included in circuit with the cinematograph motor 25, and in practice said rheostat will be so proportioned that, when the rheostat is so included, the speed of the cinematograph motor will be cut down to a point slightly below the average ratio which it is desired to maintain between the same and the phonograph motor. Thus as the two motors operate, the differential gear will be actuated to move the index or pointer forward in the direction of the arrow y in Fig. 1, so that the one end of the contact piece 36 carried by the index or pointer 23 will be caused to pass across the strip 31 of insulating material and to communicate electrically with the plate 30, as shown in Fig. 2, thereby completing the partial shunt circuit including conductors 32 and 33 and plates 29 and 30, and cutting out of the motor circuit that portion of the rheostat 28 which intervenes between said conductors 32 and 33. 110

The resistance in the cinematograph motor circuit being thus reduced, the said motor is caused to operate at an increased speed, and in setting up the apparatus for use the connection of conductor 33 with the rheostat 28 at 34 will be so arranged and adjusted that when a part of the included resistance is cut out of the cinematograph motor circuit, the said motor will be caused to operate at a speed slightly greater than the average which it is desired to maintain between the same and the phonograph motor. 120

During the operation of the cinematograph motor at this increased speed the differential gear is operated in a manner the reverse of that above described, whereby the index or pointer 23 is caused to be moved backwardly from the position shown in Fig. 2 to the position shown in Fig. 1, whereby the forward end of the contact piece 36 is 130

withdrawn from engagement with plate 30 so as to break the partial shunt circuit across that section of the resistance which is included between conductors 32 and 33, where-
5 by the current flowing in the cinematograph motor circuit is again caused to traverse the entire length of the resistance 28, with consequent reduction of the speed of said motor. Thus it will be seen that a constant suc-
10 cession of slight variations is automatically effected in the speed of the cinematograph motor, resulting in said motor being alternately operated first at a speed very slightly less than, and afterward at a speed very
15 slightly in excess of the average ratio which it is desired to maintain between said motor and the phonograph motor, but these variations are so slight and so frequently recurrent as to afford, for practical purposes, sub-
20 stantial synchronism of operation of the motors.

From the above description of my invention it will be evident that the synchronizing device constructed according to my in-
25 vention is of an extremely simple and com-
paratively inexpensive nature, and is par-
ticularly well adapted for use by reason of
the accuracy with which the desired syn-
chronous relation of the moving parts is at-
30 tained and of the substantially automatic na-
ture of its operation, and it will also be ob-
vious from the above description that the
device is susceptible of some modification
without material departure from the prin-
35 ciples and spirit of the invention, and for this
reason I do not desire to be understood as
limiting myself to the precise formation and
arrangement of the several parts herein set
forth in carrying out my invention in prac-
40 tice.

Having thus described my invention, what I claim and desire to secure by Letters Patent is—

1. A device of the character described
45 having two mechanisms, one of which is an
electric motor, and circuit controlling means
capable of operation automatically to drive
said motor alternately at two different
50 speeds, one of which is greater, and the
other of which is less than an average speed
at which it is desired to operate the other
of said mechanisms, and including a circuit
55 changer capable of reverse operation in uni-
son with reverse variations in the speed of
one of the mechanisms relatively to the
other.

2. A device of the character described
60 having two mechanisms, one of which is an
electric motor, and circuit controlling means
operable automatically to drive said motor
alternately at two different speeds, one of
65 which is greater, and the other of which is
less than an average speed at which it is de-
sired to operate the other of said mecha-
nisms, and including a resistance adapted to

be included in the motor circuit, and a cir-
cuit changer reversely operable in unison
with reverse variations in the speed of one
of the mechanisms relatively to the other, to
insert and short-circuit said resistance. 70

3. A device of the character described
having two mechanisms, one of which is an
electric motor, and circuit controlling means
operable automatically to drive said motor
alternately at two different speeds, one of 75
which is greater, and the other of which is
less than an average speed at which it is de-
sired to operate the other of said mecha-
nisms, and including a resistance insertible
in the motor circuit and adapted to be va-
ried to vary the speed of the motor, and a
circuit changer reversely operable in unison
with reverse variations in the speed of one
mechanism relatively to the other, to insert
and short-circuit said resistance. 80

4. A device of the character described,
comprising two mechanisms adapted to be
synchronously operated, means for assuring
synchronism between said mechanisms, said
means comprising an electric motor for 90
driving one of said mechanisms, a differ-
ential, one gear of which is connected to one
of said mechanisms and the other gear of
which is connected to the other of said mech-
anisms, a light resistance in the circuit of 95
said motor, and means adapted to alter-
nately cut-in and cut-out said resistance for
very short intervals and for very weak pos-
itive or negative variations of the relative
speeds of the said two mechanisms in order
100 to obtain a practically constant speed, said
means comprising a device under the control
of said differential and subject to the varia-
tions in the relative speeds of the two mech-
anisms. 105

5. A device of the character described,
comprising two mechanisms adapted to be
synchronously operated, means for assuring
synchronism between said mechanisms, said
means comprising an electric motor for 110
driving one of said mechanisms, a differ-
ential, one gear of which is connected to one of
said mechanisms and the other gear of
which is connected to the other of said mech-
anisms, a light resistance in the circuit of 115
said motor, and means adapted to alter-
nately cut-in and cut-out said resistance for
very short intervals and for very weak pos-
itive or negative variations of the relative
speeds of the said two mechanisms in order
120 to obtain a practically constant speed, said
means comprising a shunt circuit around
said resistance two contact plates connected
to terminals of said shunt circuit, and an
arm carried by said differential, movable
125 under variations in the relative speeds of
said two mechanisms, adapted to make and
break said shunt circuit.

6. A device of the character described,
comprising two mechanisms adapted to be 130

synchreously operated, both of said mechanisms being driven mechanisms, an electric motor for driving one of said mechanisms, and means for maintaining synchronism between said two mechanisms comprising a differential gearing, one mechanism being connected to one side of said gearing, and the other mechanism being connected to the other side of said gearing, and an electric controller in the circuit of said electric motor actuated by the intermediate member of said differential, said electric motor being normally adapted to maintain said mechanism driven thereby at other than the speed of said other mechanism, and said intermediate member of the differential operating

to actuate said controller to increase the speed of said motor when rotating at less than the predetermined speed, and to decrease the speed of said motor when rotating at more than the predetermined speed, whereby a substantially synchronous movement is maintained between said mechanisms. 20

In witness whereof I have hereunto signed my name this 23rd day of November, 1907, in the presence of two subscribing witnesses. 25

LÉON GAUMONT.
